UNITED STATES PATENT OFFICE.

LEON A. DANCO, OF ROCKVILLE CENTER, NEW YORK, ASSIGNOR TO MCKESSON & ROBBINS, INCORPORATED, OF BRIDGEPORT, CONNECTICUT, A CORPORATION OF CONNECTICUT.

DESIGN FOR A TRAY OR SIMILAR ARTICLE.

Application filed August 17, 1928. Serial No. 27,863. Term of patent 14 years.

To all whom it may concern:

Be it known that I, LEON A. DANCO, a citizen of the United States, residing at Rockville Center, in the county of Nassau and State of New York, have invented a new, original, and ornamental Design for a Tray or Similar Article, of which the following is a specification, reference being had to the accompanying drawing, forming a part thereof.

I claim:

The ornamental design for a tray or similar article substantially as shown.

LEON A. DANCO.
